UNITED STATES PATENT OFFICE.

HILBERT L. FALK, OF PHILADELPHIA, PENNSYLVANIA, ASSIGNOR OF EIGHT AND TWO-THIRDS THIRTY-SIXTHS TO PATRICK J. McMAHON, OF NEW ORLEANS, LOUISIANA, TEN THIRTY-SIXTHS TO GEORGE DENDINGER, OF MADISONVILLE, LOUISIANA, AND EIGHT AND TWO-THIRDS THIRTY-SIXTHS TO JACOB D. DRESNER, OF NEW ORLEANS, LOUISIANA.

GAS-IRON.

1,179,710.

Specification of Letters Patent. Patented Apr. 18, 1916.

Application filed June 1, 1914, Serial No. 842,198. Renewed January 15, 1916. Serial No. 72,373.

To all whom it may concern:

Be it known that I, HILBERT L. FALK, a citizen of the United States, residing at Philadelphia, Pennsylvania, have invented 5 certain Improvements in Gas-Irons, of which the following is a specification.

One object of my invention is to provide a novel form of gas heated iron which, in addition to including means whereby the 10 supply of gas may be conveniently regulated, shall also include means for governing the mixture of air and gas delivered to its burner.

I further desire to provide a gas iron with 15 novel gas controlling means whose construction shall be such that the supply of gas shall automatically be cut down to an amount sufficient to keep the iron properly heated when it is not in use, the arrangement of parts being such that while the iron is in operation the supply of gas is maintained at a maximum with but little effort on the part of the operator.

Another object of the invention is to provide 20 a gas iron with novel means for retaining or storing the heat from the burner in order that under operating conditions its temperature will remain substantially constant regardless of the material on which it 25 is used.

These objects and other advantageous ends I attain as hereinafter set forth, reference 30 being had to the accompanying drawings, in which,—

Figure 1 is a vertical longitudinal section 35 illustrating an iron made according to my invention, and Fig. 2 is a transverse section on a reduced scale taken on the line a—a, Fig. 1.

In the above drawings, 1 represents a hollow casting constituting the body of the iron which is of any suitable shape and size depending upon the work for which it is 40 designed, there being a cover plate 2 held in place by screws 3 closing its top opening. The body is preferably provided on each side with a relatively narrow longitudinally 45 extending opening 4 adjacent its top edge and in addition has two air holes 5 on either 50 side of the lower part of its pointed or front end, while one or more openings may be provided at its rear end to permit of its being conveniently lighted. The bottom or floor

6 of the body is, in this instance, made relatively thin and has fixed to it a comparatively thick vertically perforated plate 7 of copper, although other metals of high heat conductivity may be employed if desired without departing from my invention. 55

Mounted on the cover plate 2 in any suitable manner is a handle consisting of a U-shaped piece of relatively stiff metal strip 8 whose upper ends are connected by a curved part 9 of wood or other poor conductor of heat, such as fiber or the like. 60 This is held to the end members of the part 8 by the screws 10.

Fixed to the cover plate 2 so as to extend longitudinally within the hollow body of the iron is an L-shaped burner tube 11 whose 65 long horizontal arm has a number of openings 12 formed in its sides and under face. In the present instance, the end of this horizontal arm is closed while its vertically extending part projects through the cover 2 70 and is fixed in one end of a second L-shaped tube 13 whose second end extends through one arm of the handle strip 8 within or adjacent the vertical axial plane of the iron.

The gas supply tube 14 of the iron extends 75 through the second arm of the handle 8 and is connected to one end of a controlling valve structure 15 whose opposite end has a gas jet nozzle 16 adjacent and in line with the opening into the tube or conduit 13. 80 This nozzle consists of a conical and relatively fixed needle valve 17, concentric with which there is a series of gas outlets 18 and on it is threaded a cap 19. Said cap has a central opening which receives, and in one 85 position may be completely closed by, the valve structure 17, although ordinarily it would be sufficiently backed off to permit the gas flowing through the passages 18 to escape through said central opening. 90

In the valve structure 15 is mounted any 95 suitable form of valve 20 which, in the present instance, is of the rotatable type and has an operating arm 21 so acted on by a spring 22 as to be normally maintained in a partially open position. Pivoted to the end of this arm 21 is a rod 23 which extends upwardly through an opening in the rear part of the handle bar 9 and this rod carries on its upper end a semi-annular or suitable 100 form of head or hand piece 24 which, when

the valve 21 is in its partially closed position, is held a considerable distance above the top surface of the handle bar. It may, however, be moved downwardly against the action of the spring 22 until it engages said handle bar, at which time the valve 20 occupies its fully open position.

Under operating conditions, gas supplied to the pipe 14 is throttled by the valve 20 so that, ordinarily, the rate of flow from the gas jet nozzle into the conduit 13 and burner tube 11 is just sufficient to maintain the iron heated to a predetermined operative point, it being noted that the passage of the jet of gas under pressure from said nozzle to the tube 13 causes air to be drawn into the latter in sufficient quantities to produce the most efficient and complete combustion in the iron. When the iron is used, the grasping of the handle 9 by the operator causes the depression of the hand piece or head 24, thus fully opening the valve 20 and causing the iron to be heated to the highest point possible. At any time that the hand piece 24 is released by the operator the spring 22 at once acts to partially close the valve 20, with the result that only enough gas flows to maintain the iron ready for use.

The copper plate 7 is held in place in the bottom of the iron body by any suitable means and after being heated maintains the temperature of the iron substantially uniform at all points even though it be continuously used for long periods of time.

If desired, a deflector 25 in the form of a hood, extending longitudinally over the horizontal run of the pipe 11, may be provided to spread the gas flame over the bottom of the iron and obviously its form may be varied to suit different designs of iron without departing from my invention.

I claim—

1. The combination in a gas iron of a body; a handle; a conduit for delivering fuel into said body; a valve in said conduit;

operating mechanism for said valve including a stem extending vertically through the handle and having a portion projecting above the same; and a spring acting on the valve to normally maintain it in a partially closed position with said stem raised, said valve being movable to a full open position when the member is depressed by the hand of the operator in the act of grasping the handle.

2. The combination in a gas iron of a hollow body having a handle; a conduit for delivering fuel to said body; a valve in the conduit having an operating arm; a stem attached to said arm and longitudinally movable through an opening in the handle; a spring operative to hold the stem in an elevated position and the valve partially closed; and a head for said stem projecting beyond the handle in a position to be depressed when said handle is grasped by the operator.

3. The combination in a gas iron of a hollow metal body having a relatively thin bottom; a vertically perforated copper plate mounted within said body in engagement with the bottom thereof; a burner extending in the body adjacent said plate; and means for delivering fuel to said burner.

4. The combination in a gas iron of a hollow body; a cover therefor; a perforated burner tube extending within the same and terminating in a horizontal open portion adjacent the cover; a gas jet nozzle for the conduit spaced away from but in line with the opening in the burner tube and mounted directly upon said cover under the handle; with means for controlling the flow of fuel to said nozzle.

In testimony whereof, I have signed my name to this specification, in the presence of two subscribing witnesses.

HILBERT L. FALK.
